United States Patent Office

Des. 218,857
Patented Sept. 29, 1970

218,857

AIRCRAFT

Walter E. Fellers, Los Angeles, Leon F. Begin, Pasadena, John W. Patierno, Huntington Beach, Michael G. Huben, Los Angeles, Adam L. Roth, Palos Verdes Estates, Hans W. Grellmann, Torrance, and Vernon L. White, Los Angeles, Calif., assignors to Northrop Corporation, Beverly Hills, Calif., a corporation of California

Filed June 30, 1969, Ser. No. 17,969

Term of patent 14 years

Int. Cl. D12—07

U.S. Cl. D71—1

FIG. 1 is a perspective view viewed from above of the aircraft employing our new design;

FIG. 2 is a top plan view thereof;

FIG. 3 is a side elevational view thereof, the opposite side thereof being identical; and

FIG. 4 is a front elevational view thereof.

We claim:

The ornamental design of an aircraft, substantially as shown and described.
